UNITED STATES PATENT OFFICE.

HAROLD ROWNTREE, OF CHICAGO, ILLINOIS.

PASSENGER-CAR.

935,929.

Specification of Letters Patent. Patented Oct. 5, 1909.

Application filed May 21, 1908. Serial No. 434,007.

To all whom it may concern:

Be it known that I, HAROLD ROWNTREE, a citizen of the United States, residing at Chicago, in the county of Cook, State of Illinois, have made a certain new and useful Invention in Passenger-Cars, of which the following is a specification.

This invention relates to passenger cars.

The object of the invention is to provide 10 a passenger car for street or other railways embodying means which are simple in construction and arrangement whereby the collection of fares as the passengers enter the car is facilitated.

15 Other objects of the invention will appear more fully hereinafter.

The invention consists substantially in the construction, combination, location, and relative arrangement of parts, all as will be more 20 fully hereinafter set forth, as shown in the accompanying drawings, and finally pointed out in the appended claims.

Referring to the accompanying drawings, and to the various views and reference signs 25 appearing thereon: Figure 1 is a view in horizontal section of a passenger car embodying the principles of my invention. Fig. 2 is a vertical transverse section of the same. Fig. 3 is a view partly in side elevation, and partly in vertical longitudinal section. Fig. 4 is a view similar to Fig. 1 showing a somewhat different arrangement embodying the principles of my invention. Fig. 5 is a view in vertical transverse section 35 of the car shown in Fig. 4.

The same part is designated by the same reference sign wherever it occurs throughout the several views.

The problem of handling the street and 40 other passenger car traffic, and particularly in the larger cities, where such traffic already heavy is constantly increasing, has become a most serious one. Where, during certain hours of the day, the traffic is very 45 heavy the car conductors frequently find it impossible to collect fares from all the passengers on account of the large numbers of passengers who crowd themselves into the cars, and, not infrequently unscrupulous 50 conductors utilize the congestion of traffic on the cars to dishonestly enrich themselves at the expense of the company by neglecting or failing to register a portion of the fares collected from the passengers. In either 55 event the street or other passenger car com-

pany suffers loss of revenue in a failure to receive the full return of fares for all the passengers transported. Many expedients have been resorted to in the endeavor to overcome this objection and to avoid losses 60 incident thereto. Among other methods adopted is the use of what is commonly styled "pay as you enter" cars in which the fare of each passenger is collected as such passenger enters the car. In the construction 65 of cars commonly employed in connection with this method a railing is employed on the platforms at the ends of the car which is so arranged as to provide a separate entrance and exit passage to and from the 70 car by means of which passengers enter the car singly through one passage, their fares being collected by a conductor as they enter, while they leave the car through the other passage, thereby insuring the collection of 75 the fare from each passenger as the passenger enters the car, the conductor being stationed on the platform outside the car body and the door way leading into the car and in convenient position with reference to the 80 entrance passage. Two important disadvantages are experienced with cars having this arrangement. In the first place the conductor is located on the outside of the 85 car and hence is enabled to collect fares without registering them and it is difficult to detect the dishonesty since any inspector who might board the car will be required to pass inside the car, thereby rendering it 90 difficult for him to observe whether a passenger entering the car delivers a transfer or a cash fare to the conductor, the latter being stationed on the outside of the car. In the next place the location of the railing 95 on the platform to provide the separate entrance and exit passages necessitates a material increase in platform space and a consequent increase in cost of construction of the car without any increase in carrying capacity of the car. This expense arises by 100 reason of the necessity of extending the car roof as well as the floor to provide the necessary increased platform area, and also the necessity of providing braces to properly support the extended platform. This objection is particularly burdensome where it is 105 desired to convert the cars already in use into the "pay as you enter" style.

My invention relates to passenger cars of this class and operated on the "pay as you 110

enter" plan and the particular object sought is to provide means which are very simple and inexpensive whereby the fares are collected from the passengers as they enter the 5 car, whereby the conductor is always in plain view of passengers or inspectors on the inside of the car, who can thereby more readily detect any attempted dishonesty in failing to ring up or register the fares collected, and whereby the ordinary cars at 10 present in use, may be readily and easily converted, at small expense into condition for use upon the "pay as you enter" plan.

In carrying out my invention I propose to 15 employ a railing or other suitable or convenient form of partition and which is arranged to extend into the body of the car from or adjacent the doorway or entrance, in such 20 relation as to provide a restricted entrance passage through which the passengers pass in entering the car and whereby the conductor can readily and easily collect the fares, from a point inside the car, from the 25 passengers as they enter the car. By providing this restricted entrance passage the conductor is enabled to operate either close to the doorway, when the traffic is light, or at any 30 convenient point along the entrance passage in case the passengers enter the car in considerable numbers, as at busy corners or 35 stations, or during the hours of heavy traffic, thereby facilitating the work of the conductor and from a point where his operations are constantly in plain view. I also 40 propose to so arrange the railing or partition as to also provide a separate passage which may, if desired, be utilized as an exit 45 passage from the car or which may provide a space for the conductor, the railing extending, preferably, or in one form of application of my invention, lengthwise of the 50 car.

It is obvious that my invention may be carried into practical operation with various 55 styles and types of cars. While, therefore, I have shown and will now describe my invention as applied to certain styles or types and arrangement of passenger cars, it is to be understood that I am not to be limited 60 or restricted in this respect.

Referring to Figs. 1, 2 and 3, reference sign 6 is the car body, 7 vestibule ends thereof, and 8 wall seats extending lengthwise of the car. If desired, and as shown, 65 each end of the car may be provided with a vestibule 7, and a motorman's controller 9, in the usual way. The vestibules, may be provided with a door 10, 11, on one or both sides thereof, as may be desired, and the 70 usual or any desired construction or arrangement of steps 12, may be employed. The doors may be movable, and in the drawings I have shown sliding doors, though my invention is not to be limited or restricted in this 75 respect. The doors may be operated in any

suitable or convenient manner. In the form shown as exemplifying the principles of my invention I provide suitable connections, 13, to the door on one side of the vestibule and designed to be used at one end of the car 70 for the entrance of passengers, and I provide means, indicated at 14 and 15 whereby the door operating connections may be controlled by the conductor or the motorman respectively. If desired, and as usual, a fare 75 register 16, may be arranged at each end of the car.

The parts so far described may be of the usual or any desired construction and in the specific structure thereof form no part of 80 my present invention.

A railing or partition 18 is arranged to extend from the end wall of the vestibule into the body of the car, and, in the particular construction shown, lengthwise of the car 85 thereby forming the entrance passageway 19, and, if desired, an exit passageway 20, into and from the body of the car.

In practice the motorman is stationed in the vestibule at the front end of the car, 90 and when passenger's desire to leave the car they leave through the front door or doors which are opened and closed by the motorman, or otherwise, as may be most convenient. The conductor is stationed at the rear 95 end of the car, and in the passage 20, from which position he may readily control the doors at that end of the car. Under ordinary conditions only one door is used at this rear end of the car, and this door, indicated 100 by reference sign 10, is employed only as an entrance door. When passengers get on the car they enter through the door 10, and passing down the car through the restricted passage 19, formed by the railing, they 105 give their fares to the conductor who occupies the passage 20. If the traffic is light the conductor occupies a position closely adjacent the door and collects the fares from that point. He has the freedom, however, 110 of the entire length of the passage 20, which is determined by the length of the partition or railing 18, and hence, if the traffic is heavy, or if passengers enter the car in large numbers then the conductor may move back 115 and forth along the passage 20, and so collect the fares of all the passengers as they enter the car. It is obvious that, if desired, the other door 11, at the rear end of the car may also be used as an exit for passengers, though ordinarily the passengers will be required to leave the car from the 120 front end.

It may be sometimes desired to use the same door 10, for the entrance as well as 125 the exit of passengers. In this event I may employ a gate 21, in the railing 18, when such railing is used and by means of which passengers may leave the car through the passage 20, the gate 21, and the door 10, 130

while other passengers are entering the car through the door 10, and passageway 19.

In practice the railing or partition is preferably arranged somewhat to one side 5 of the center line of the car, as shown, whereby the entrance passageway 19, is wider than the other passageway 20, though my invention is not to be limited or restricted in this respect.

10 If desired, and as shown, a railing or partition may be provided at each end of the car so as to avoid the necessity of shifting the railing bodily from one end of the car to the other when the direction of travel of the 15 car is changed.

10 In the type of car above described the vestibule forms a continuation of the car body there being no other doorway besides those controlled by the side doors 10, 11. 20 The principles of my invention, however, are equally well adapted for use in connection with other types and styles of cars. For instance, in Figs. 4 and 5, I have shown my invention as applied to the ordinary 25 style of street car having the end platforms 22, and having the side steps 12, these platforms being separated from the inside of the car by the doors 23, in the usual manner, and operated by connections 24, from any 30 convenient point, as for instance, from the motorman's station, as indicated at 25, or from any other convenient point. In this type of car the railing 26, is arranged inside the car, and extends from a point adjacent 35 the doorway lengthwise of the car a distance sufficient to form the restricted passageways 27, 28, of extended length into the car. The conductor is stationed in one of these passageways, as 28, while passengers 40 entering the car pass through the other passageway 27, and deliver their fares to the conductor as they enter. In this case the conductor is always on the inside of the car where he may be constantly under the observation of an inspector or other passenger 45 who might desire to watch him. It is also obvious that instead of the passengers entering the car at one end and leaving it at the other end, they may enter and leave the 50 car at the same end, using the restricted passageway 27, to enter the car and the passageway 28, to leave the car.

It is obvious that my invention may be applied to other styles and designs of cars.

55 From the foregoing description it will be seen that I provide an exceedingly simple and efficient "pay as you enter" arrangement which avoids the necessity for providing an enlarged area of platform, and which 60 can be applied with ease and economy to cars of the ordinary construction without involving any material change in the structure thereof.

Having now set forth the object and nature of my invention and various modes of

application thereof, what I claim as new and useful and of my own invention and desire to secure by Letters Patent is:—

1. A passenger car having a main-body structure with the entrance and exit ways located adjacent the point where the aisle portions joins with a platform provided with doors movable lengthwise of the car, a manual operating device located to define the entrance and exit ways from the platform 70 to the body of the car and mechanism located under the car and connected with said manual operating device for moving one of said doors.

2. A passenger car provided with a platform having movable sides, said platform directly connected with an unobstructed internal portion of the car where merging with the platform and means located within said portion to define the entrance and exit 85 ways from a platform to the body of the car and to control the movement of said platform sides.

3. A passenger car having a main car body and an end vestibule, the car body space 90 merging unobstructedly into the vestibule space, a door and a doorway in the side of the vestibule, and means located between the car body space and the door for operating the latter.

4. A passenger car having a main body structure and an end vestibule, the aisle space of the body structure opening unobstructedly its full width into the vestibule space, a side door for the vestibule, and 100 means arranged in the said opening for controlling the operation of the door.

5. A passenger car having a body space and an end vestibule, said vestibule having a movable side door, the body space merging 105 unobstructedly into the vestibule space, and means for controlling the movements of the side door, said means located adjacent said point of mergence.

6. A passenger car provided with a main 110 car body and an inclosed end vestibule, the car body space merging unobstructedly into the vestibule space, a movable door in the side of the vestibule, means for moving said door, and means located adjacent said point 115 of mergence for controlling said door moving means.

7. A passenger car provided with wide entrance and exit ways at one end of the main car-body structure where merging with a platform having movable portions and means provided with a lever for actuating said movable portions and located to define the entrance and exit ways from the platform to the main car body.

8. A passenger car provided with wide entrance and exit ways at both ends of the main car-body structure directly connected with an inclosed platform having a movable side and means for actuating said side 130

and operatively controlled by a conductor through a lever located to provide the entrance and exit ways from the platform to the main car body.

5. A passenger car having a main car body structure provided with an end opening wider than that of the aisle within the car body at the point where merging into a platform, and means in said opening to form the conductor's station, and thereby dividing by the conductor's station said opening into passageways to and from the main car body structure with said platform.

10. A passenger car having a car body and a side door, an unobstructed passage leading from the side door into the car body, and means located within the car body to define entrance and exit ways through said passage, and to operate the door.

15. 11. A passenger car having a car body and separate entrance and exit ways into and from the aisle space of the car body, a movable door, and means located within the car and between the entrance and exit ways for controlling the operation of the door.

20. 12. A passenger car having a car body and an end platform, said platform having a side door, and also merging unobstructedly into the car body, and means located within the car body to define entrance and exit ways through said passage and to operate the door.

25. 13. A passenger car having a body space

and a platform space merging unobstructedly into each other, a side door for the platform, and means located within the car body space for controlling the operation of the door.

30. 14. A passenger car having a door, means arranged inside the door to divide the space inside the door into separate entrance and exit passages, and means also arranged inside the door but removed therefrom for controlling the operation of the door.

35. 15. A passenger car having an end vestibule, a side door for the vestibule; and means located inside the door for operating the door, said means serving to divide the space inside the door into separate entrance and exit passages.

40. 16. A passenger car having an end vestibule, a side door therefor, means located inside the door to divide the space inside the door into separate entrance and exit passages, and means also located inside the door, 45 and adjacent said passage separating means for controlling the door movements.

45. In testimony whereof I have hereunto set my hand in the presence of the subscribing witnesses, on this ninth day of May A. D., 60 1908.

HAROLD ROWNTREE.
